(**) Term: **14 Years**

CLAIM

(21) Appl. No.: **29/097,522**

The ornamental design for a surface configuration of a rear panel for a vehicle, as shown and described.

(22) Filed: **Dec. 9, 1998**

DESCRIPTION

(30) **Foreign Application Priority Data**

FIG. 1 is a front view of a surface configuration of a rear panel for a vehicle according to my novel design;
FIG. 2 is a right side view of a surface configuration of a rear panel for a vehicle according to my novel design;
FIG. 3 is a top view of a surface configuration of a rear panel for a vehicle according to my novel design;
FIG. 4 is a bottom view of a surface configuration of a rear panel for a vehicle according to my novel design; and,
FIG. 5 is a perspective view from the front right of a surface configuration of a rear panel for a vehicle according to my novel design.

(51) LOC (7) Cl. **12-16**

The broken line included depicts environment and is not part of the claimed design.

(52) U.S. Cl. **D12/196**; D12/169

(58) Field of Search **D12/196, 169; 293/113, 117, 120, 115; 296/180.1, 180.2**
